UNITED STATES PATENT OFFICE

120,862

DESIGN FOR A COMBINED SHELF AND SUPPORT THEREFOR

George Heisler, Wooster, Ohio, assignor to The Fredericksburg Art Pottery Company, Fredericksburg, Ohio, a corporation of Ohio

Application March 11, 1940, Serial No. 90,833

Term of patent 3½ years

To all whom it may concern:

Be it known that I, George Heisler, a citizen of the United States, residing at Wooster, in the county of Wayne and State of Ohio, have invented a new, original, and ornamental Design for a Combined Shelf and Support Therefor, of which the following is a specification, reference being had to the accompanying drawing, forming part thereof.

I claim:

The ornamental design for a combined shelf and support therefor, as shown.

GEORGE HEISLER.
